Primary Examiner — Bridget L Eland(74) *Attorney, Agent, or Firm* — Buchanan Ingersoll & Rooney PC(57) **CLAIM**

The ornamental design for a remote input output power supply module, as shown and described.

DESCRIPTION

FIG. 1 is a right side perspective view of a remote input output power supply module according to our new design.

FIG. 2 is a left perspective view thereof.

FIG. 3 is a front perspective view thereof.

FIG. 4 is a rear perspective view thereof.

FIG. 5 is a top perspective view thereof.

FIG. 6 is a bottom perspective view thereof.

FIG. 7 is a front elevational view thereof.

FIG. 8 is a rear elevational view thereof.

FIG. 9 is a top plan view thereof.

FIG. 10 is a bottom plan view thereof.

FIG. 11 is a left side elevational view thereof; and,

FIG. 12 is a right side elevational view thereof.

The wireframe lines shown throughout the views are intended to indicate surface contour and are not intended to be surface ornamentation.
